MEANS FOR SUPPLYING FUEL TO FURNACES

Application filed January 10, 1930, Serial No. 419,963, and in the Netherlands January 15, 1929.

This invention relates to full-automatic means for supplying fuel such as bagasse, peat, saw-dust etc. to a furnace, more especially to a boiler furnace.

Various suggestions have been made to mechanically supply bagasse to a boiler furnace, but as far as we are aware, the rate of feed in said known devices can only be controlled by hand. Since the amount of fuel to be supplied per unit of time is variable and dependent, inter alia, upon the chimney draft, the caloric value of the fuel (which especially with bagasse varies within wide limits) and the condition of the fire (amount of clinker on the grate), such a mechanical stoker obviously requires to be repeatedly adjusted.

The object of our present invention is to avoid the necessity of manually adjusting the rate of feed and to automatically control said rate responsive to requirements. With this object in view, we suggest to provide a charging receptacle mounted directly in front of and in communication with the furnace mouth and adapted for vertical displacement under the influence of gravity, in combination with a conveyor or the like for supplying fuel to said receptacle and with means operatively coupling the driving mechanism of the conveyor with the receptacle in such a manner that vertical displacement of the receptacle controls the speed of the conveyor, i. e. the rate of feed. In most cases it will suffice to simply allow the said receptacle to stop the conveyor whenever the weight of the fuel accumulated therein exceeds a predetermined value.

In order that our invention may be fully understood we shall now proceed to describe the same with reference to the annexed more or less diagrammatic drawing, which illustrates by way of example only a preferred embodiment thereof in elevational section.

B symbolizes one of a battery of boilers, 1 a carrier or other conveyor of any suitable or approved construction extending horizon-

tally along the front of said battery and spaced a suitable distance apart therefrom. Said conveyor receives fuel, for instance, bagasse, from an elevator or the like, not shown. Provided in front of each boiler B and vertically below the conveyor 1 is a bunker 2 which is continuously kept filled with bagasse by said conveyor. This bunker discharges the fuel, in a layer of predetermined thickness, onto a second conveyor 3, which carries it towards the boiler in the direction of the arrow. The cross sectional area of the discharge opening, formed between the front wall 4 of the bunker 2 and the upper part of the conveyor 3, can be adjusted by means of a slide valve 5. The remaining walls of the bunker extend close to said upper part.

The conveyor 3 discharges the bagasse into an inclined chute 6, which is pivoted as at 7 to the cast iron mouth 8 of furnace F, so as to be adapted for vertical swinging movement relative thereto.

The conveyor 3 is driven by a ratchet wheel 9 cooperating with a ratchet 10 pivoted to an arm 11 loosely mounted on the shaft 12 of the front drum of said conveyor. Swinging motion is imparted to arm 11 through the rod 15 of an eccentric 14 mounted on a driving shaft 13 located at the rear side of the conveyor 1. As long as the ratchet 10 engages the ratchet wheel 9, forward swinging motion of arm 11 will cause the said wheel to rotate the drum of the conveyor 3 through a predetermined angular distance, whereby a suitable amount of bagasse will be supplied to the chute 6.

The bagasse in the chute 6 moves by gravity to the furnace mouth 8, the rate of feed being entirely dependent upon the amount of fuel consumed in the furnace, it being understood that the slide valve 5 should be so adjusted as to always allow a sufficient amount of bagasse to be discharged onto the carrier 3.

to supply the chute 6 with the required quantity.

Under normal conditions, i. e. as long as the bagasse in chute 6 does not exceed level S^1 , said chute assumes the position 6' under the gravity pull of a counterweight 18 resting on a platform 16. If, however, owing to reduced consumption of fuel in the furnace, the amount of bagasse accumulated in the pivotally mounted chute 6 rises above said level S^1 , the chute 6 swings downward through a small angular distance, pulling the counterweight 18 upward until assuming its extreme position 6'' determined by an abutment 17. As a consequence of this downward swinging motion of the chute, the ratchet 10 is caused to disengage the ratchet wheel 9. This is effected, in the embodiment shown, by a chain 19, the lower end of which is secured to the upper end of the pivoted chute 6, whereas its other end engages the tail of the ratchet 10 in such a manner that sufficient pull on chain 19 will force the pawl 10 out of engagement with the ratchet wheel against the action of a spring 20, which tends to keep the ratchet in operative engagement therewith. It will be understood that the conveyor 3 will then be stopped and the supply of bagasse to the chute 6 interrupted.

Also in its lower position 6'' the chute 6 has sufficient inclination to allow the bagasse accumulated therein to slide by gravity into the furnace, so that, after a certain time, the amount of fuel in said chute will decrease to a sufficient degree to allow the counterweight 18 to again pull the chute into its normal position 6', whereby the chain 19 is slackened and spring 20 again forces ratchet 10 into engagement with its ratchet wheel.

As shown on the drawing, the chute 6 extends a certain distance above level S^1 , so that the fuel therein can rise to an appreciably higher level S^2 . Therefore, even if there is considerable frictional resistance or clearance in the parts through which chute 6 is operatively coupled with ratchet 10, the latter is positively disengaged from its ratchet wheel 9 before the fuel can overflow the chute.

In the embodiment shown, the arm 11 has an elongated slot 11a, whereas the eccentric rod 15 engages a pin 15a extending into said slot and adapted to be secured in any desired position therein, so that the operative length of arm 11, that is to say its angular stroke and consequently the speed of the conveyor 3 can be adjusted to suit requirements. With this arrangement, the slide valve 5 could be dispensed with.

What we claim is:—

1. Means for supplying fuel such as bagasse, peat, saw-dust or the like to a furnace, a receptacle mounted opposite and in communication with the furnace mouth and arranged for vertical displacement under

the influence of gravity, means for supplying fuel to said receptacle, and means operatively coupling said fuel supplying means with said receptacle in such a manner that vertical displacement of the receptacle controls the rate of supply. 70

2. In means for supplying fuel such as bagasse, peat, saw-dust or the like to a furnace, a receptacle mounted opposite and in communication with the furnace mouth and arranged for vertical displacement under the influence of gravity, a conveyor for supplying fuel to said receptacle, driving mechanism for said conveyor, and means operatively coupling said receptacle with said driving mechanism in such a manner that vertical displacement of the receptacle controls the rate of speed of said conveyor. 75

3. In means for supplying fuel such as bagasse, peat, saw-dust and the like to a furnace, an inclined chute merging into the furnace mouth and mounted for vertical swinging motion relative thereto, means such as a counterweight tending to keep said chute in an upper inclined position, a conveyor for supplying fuel to said chute, a driving shaft, means operatively coupling said shaft with said conveyor, and means adapted under the influence of downward swinging motion of said chute to disengage said shaft from said conveyor. 80

4. In means for supplying fuel such as bagasse, peat, saw-dust and the like to a furnace, an inclined chute merging into the furnace mouth and mounted for vertical swinging motion relative thereto, means such as a counterweight tending to keep said chute in an upper inclined position, a conveyor for supplying fuel to said chute, a ratchet wheel adapted to drive said conveyor, a driving shaft, an offset part such as an eccentric on said shaft, a rod associated with said offset part, a lever adapted for swinging movement about the axis of said ratchet wheel and associated with said rod, a ratchet pivotally mounted on said lever, means such as a spring tending to keep said ratchet in operative engagement with said ratchet wheel, and means such as a chain connecting said chute with said ratchet in such a manner that downward swinging motion of said chute tends to disengage said ratchet from said ratchet wheel. 100

5. In means for supplying fuel such as bagasse, peat, saw-dust and the like to a furnace, an inclined chute merging into the furnace mouth and mounted for vertical swinging motion relative thereto, means such as a counterweight tending to keep said chute in an upper inclined position, an abutment positively preventing said chute from swinging downward beyond a lower inclined position, a conveyor for supplying fuel to said chute, a ratchet wheel adapted to drive said conveyor, a driving shaft, an offset part such as an eccentric on said shaft, a rod associated 110

with said offset part, a lever adapted for swinging movement about the axis of said ratchet wheel and associated with said rod, means for adjusting the operative length of said lever, a ratchet provided to said lever, means such as a spring tending to keep said ratchet in operative engagement with said ratchet wheel, and means such as a chain connecting said chute with said ratchet in such a manner that downward swinging motion of said chute tends to disengage said ratchet from said ratchet wheel.

5 In testimony whereof we affix our signatures.
